UNITED STATES PATENT OFFICE.

OTTO A. FRITZ, OF MELROSE, MASSACHUSETTS.

WINDOW SCREEN.

Application filed January 31, 1928. Serial No. 250,877.

This invention relates to window screens and has for its object to provide, in a manner as hereinafter set forth, a screen of such class so constructed and arranged to enable the 5 sliding and tilting thereof when desired, and further whereby the screen can be latched in perpendicular position with respect to a window frame to prevent tilting of the screen when vertically adjusting it.

Further objects of the invention are to provide, in a manner as hereinafter set forth, a window screen for the purpose referred to which is comparatively simple in its construction and arrangement, strong, durable, 15 compact, thoroughly efficient in its use, conveniently adjusted, readily installed with respect to a window frame and comparatively inexpensive to manufacture.

With the foregoing and other objects in view the invention consists of the novel construction, combination and arrangement of parts as hereinafter more specifically described, and illustrated in the accompanying drawings, wherein is shown an embodiment 25 of the invention, but it is to be understood that changes, variations and modifications can be resorted to which fall within the scope of the claims hereunto appended.

In the drawings wherein like reference characters denote corresponding parts throughout the several views:

Figure 1 is a fragmentary view in elevation of a window frame showing the adaptation therewith of a window screen in accordance with this invention.

Figure 2 is a section on line 2—2 Figure 1. Figure 3 is a section on line 3—3 Figure 1. Figure 4 is a section on line 4—4 Figure 1. Figure 5 is a fragmentary view in perspective of the window screen and showing one form of latch member for retaining the screen in a perpendicular position with respect to the window frame.

Figure 6 is a section on line 6—6 Figure 3. Figure 7 is a fragmentary view in perspective of the frame of the screen and further illustrating one of the track swings carried by such frame.

Figure 8 is a fragmentary view in elevation of a window screen and showing a modified form of latching member therefor.

Referring to the drawings in detail 1 and 2 indicate the sides of a window frame and 3 the bottom rail of the latter. Secured to the 55 inner faces of the sides 1, 2 are guide rails or stiles 4, 5 respectively and which consti-

tute tracks for a pair of track swings, to be hereinafter referred to, and which are carried by the screen frame. The guide rails or stiles 4, 5 will be hereinafter termed the track. 60 Projecting from the inner faces of the sides 1, 2 are pins or studs 6 which provide stops for the track swings to be presently referred to.

A window screen, in accordance with this invention, comprises a frame formed of a top rail 7, a bottom rail 8 and a pair of side rails 9, 10. Extending across the opening formed by the screen frame, as well as being secured to the rails 7 to 10 inclusive is a foraminous panel 11. As shown by way of example the window screen is of rectangular contour. The outer side edges of the rails 9, 10 and the end edges of the top and bottom rails 8 are rabbeted, as indicated at 12 to oppose the outer side edges of the track 75 and also one face thereof. See Figure 4. The rabbets of the rails 7, 8 form continuations of the rabbit in the rails 9, 10. Binding strips 13 are employed for securing the panel 11 to the screen frame and the rails of the latter 80 are rabbeted as at 14 to provide a seat for the marginal portions of the panel 11. See Figure 4.

Positioned at the ends of the top rail 7 of the screen frame are track swings 15, 16. The track swings are oppositely disposed with respect to each other and each of which consists of a channel shaped body portion 17, having one side thereof terminating in a right angularly disposed flange 18 corresponding in length to the length of the body portion 17 and provided with openings 19, 20. The flange 18 is pivotally connected at its upper end to the non-rabbeted part of a side of the screen frame by the pivot 21 which extends through the opening 19. The opening 20 is provided for the passage of a holdfast device to fixedly secure the swings to the screen frame when desired. Normally the swing and screen frame pivot relatively to 100 each other. The body portion 17 straddles a track and also constitutes a guide for the screen when it is moved upwardly and further prevents the upper portion of the screen from disconnecting from the track. The screen can be slid upwardly to the desired point and then shifted on the pivot 21, as illustrated in dotted lines in Figure 2.

Carried at the lower portion of the window screen is a pair of oppositely disposed latching members 22, 23 and each of which consists of a lengthwise slotted strap 24 having an 110

inwardly extending angularly disposed stop portion 25 for limiting the outward shift of the latch member. Set screws 26 are provided for detachably securing the latching member in set position. The latching members are adapted to be shifted outwardly with respect to the sides of the frame of the screen for the purpose of opposing the track and when in such position, in connection with the 10 non-rabbeted portion of the screen frame maintains the screen in perpendicular position with respect to the window frame and when the latching members are arranged in such position the screen can be vertically adjusted and slidably coupled to the tracks 4, 5.

Carried by the body portion of each track swing, as well as arranged therein, is a resilient member 27, in the form of an arcuate spring for frictionally coupling the swing to 20 the track, but the coupling is such as not to interfere with the vertical shifting of the frame, that is to say the screen frame, when desired. The resilient members 27 also provide means to prevent the shifting of the 25 swings on the track when the screen is tilted.

In Figure 8 a modified form of latching member is shown and which consists of a pivoted strap 28 connected to a side rail 9 or 10 near the lower portion thereof and provided 30 at its inner end with an angularly disposed stop 29 for limiting the pivoting movement in either direction of the strap 28. The pivot for the strap 28 is indicated at 30.

To remove the screen it is necessary to tilt 35 it outward and then tip it up and after such operation the screen can be removed from the tracks.

It is thought the many advantages of a 40 window screen, in accordance with this invention, can be readily understood, and although the preferred embodiment of the invention is as illustrated and described, yet it is to be understood that changes in the details 45 of construction can be had which will fall within the scope of the invention as claimed.

What I claim is:

1. In a window screen a frame provided 50 with a transparent panel and having a portion of each side rabbeted lengthwise thereof for opposing the free side edge and one face of a window guide rail, a pair of oppositely disposed swings opposing the non-rabbeted and rabbeted portions of the sides of said frame and adapted to be slidably mounted on 55 and overlap the window guide rails, and means for pivotally connecting the screen frame to that portion of the swings opposing the non-rabbeted portion of the frame whereby said frame can be tilted on said pivots.

2. In a window screen a frame provided 60 with a transparent panel and having a portion of each side rabbeted lengthwise thereof for opposing the free side edge and one face of a window guide rail, a pair of oppositely disposed swings opposing the non-rabbeted

and rabbeted portions of the sides of said frame and adapted to be slidably mounted on and overlap the widow guide rails, means for pivotally connecting the screen frame to that portion of the swings opposing the non-rabbeted portion of the frame whereby said frame can be tilted on said pivots, and friction clutching means between said window guide rails and swings to maintain said swings normally stationary. 70

3. In combination a screen having a portion of each of its sides rabbeted, a pair of vertically slidable track swings seating in said rabbeted portion, and means for pivotally connecting said screen at the top of the 80 non-rabbeted portions of said sides to said swings whereby the screen can tilt relatively to the swings.

4. In combination a screen having a portion of each of its sides rabbeted, a pair of vertically slidable track swings, seated in the rabbeted portions of said sides, means for pivotally connecting said screen at the top of the non-rabbeted portions of said sides to 85 said swings whereby the screen can tilt relatively to the swings, and frictional clutching means carried by the swings for normally 90 maintaining them stationary.

5. In combination a window screen having 95 its sides rabbeted, vertically slidable track swings seating in said rabbets and including flanges projecting from the rabbets, and means for pivotally connecting said screen at one end of the non-rabbeted portions of its sides to the flanges of said swings whereby 100 the screen can be tilted relative to said swings.

6. In combination a window screen having 105 its sides rabbeted, vertically slidable track swings seating in said rabbets and including flanges projecting from the rabbets, means for pivotally connecting said screen at one end of the non-rabbeted portions of its sides to one end of the flanges of said swings whereby the screen can be tilted relative to said swings, and frictional clutching means carried by the 110 swings for normally retaining them stationary.

7. In combination a window screen, channel-shaped, vertically slidable track swings each provided with a lateral flange, and pivot 115 means between the upper part of said flanges and the sides of said screen at the part of the latter whereby the screen can tilt relative to the swings.

8. In combination a window screen, channel-shaped vertically slidable track swings each provided with a lateral flange, pivot means between the upper part of said flanges and the sides of said screen at the upper part 120 of the latter whereby the screen can tilt relative to the swings, and frictional clutching means carried by said swings for normally 125 retaining them stationary.

9. In combination a window screen, channel-shaped, vertically slidable track swings 130

for overlapping window guide rails and each provided with a lateral flange extending from said rails, pivot means between said flanges and the sides of said screen at the top of the latter whereby the screen can tilt relative to the swings, and stops for positioning adjacent guide rails and providing for arresting the sliding movement of the swings in one direction.

10. 10. In combination a window screen, channel-shaped, vertically slidable track swings for overlapping window guide rails and each provided with a lateral flange extending from said rails, pivot means between said flanges and the sides of said screen at the top of the latter whereby the screen can tilt relative to the swings, frictional clutching means for engagement with the window side rails and carried by said swings for normally retaining them stationary, and stops for positioning adjacent window guide rails and providing for arresting the sliding movement of the swings in one direction.

11. In combination, a vertically shiftable screen frame having a portion of each side thereof rabbeted from end to end to oppose the free edge and one side face of a window guide rail, a pair of oppositely disposed track swings opposing the non-rabbeted and rabbeted portions of said sides and adapted to overlap and travel on said guide rails, pivotal connections between the top of said non-rabbeted portions and that part of the swings opposing such portions whereby the swings will be carried with the frame and the latter

35 will be carried with the frame and the latter

can be swung at an angle with respect to the guide rails, means arranged in said swings for coaction with the free edge of the guide rails to normally clutch the swings stationary, and releasable means carried by the frame for coaction with the other side face of the guide rails to arrest the swinging movement of the frame.

12. In combination, a vertically shiftable screen frame having a portion of each side thereof rabbeted from end to end to oppose the free edge and one side face of a window guide rail, a pair of oppositely disposed track swings opposing the non-rabbeted and rabbeted portions of said sides and adapted to overlap and travel on said guide rails, pivotal connections between the top of said non-rabbeted portions and that part of the swings opposing such portions whereby the swings will be carried with the frame and the latter 50 can be swung at an angle with respect to the guide rails, means arranged in said swings for coaction with the free edge of the guide rails to normally clutch the swings stationary, and releasable means carried by the frame 55 for coaction with the other side face of the guide rails to arrest the swinging movement of the frame, and stops for connection to the last mentioned side faces of the rails and positioned in the path of the lower ends of 60 said swings.

In testimony whereof, I affix my signature hereto.

OTTO A. FRITZ.
